the handle on the other panel. To insure against pulling out of the panels in the load carrying positions the flanges 20 are widened across the arched portion to provide greater overlap.

When the container is resting on a support such as a table top and a panel 28 is moved to open position its outer edge 34 will contact the table top, which will prevent its unintentional removal from the guideways. If it is desired, an inwardly extending stop 38 may be provided immediately below the handle 36. The stop will normally engage the upper edge of wall 14 but, since there is some flexibility in the parts, they may be spread far enough to allow the stop to pass along the outer surface of the wall to disengage the panel 15 from the guideways.

The curvature of the medial portion of the panel when in the closed position gives it sufficient stiffness to resist bending loads. The elongated handle member 36 stiffens the inner edge and similar stiffening may be obtained at the outer edge by applying a reinforcing member 40. This member also serves as a handle or abutment for opening the panel by downward pressure on the abutment.

The casing may be made of any desired material, such as metal or plastic. The latter material when sliding on similar material tends to bind and gall. This difficulty can be overcome by providing anti-friction material 41 on the bearing portion of the panel. The material may be of any type having satisfactory properties such as metal or cloth. One which has been found satisfactory is a flock of fibrous material.

Altho the container may have any desired general outline the form shown in Figure 2 is relatively wide and low so that when serving as a lunch box it will accommodate two vacuum bottles side by side. These bottles 42, shown in phantom lines, are supported on brackets 44, one on each end wall 16. The brackets are double arched to hold the bottles in spaced relation and, as seen in Figure 6, extend inwardly beyond the flanges 20 so that a bottle which will pass the flanges will properly contact the brackets. The latter are located well above the bottom 12 to provide space for sandwiches or other items. When one panel 28 is opened it provides sufficient space for the passage of one bottle.

In the more conventional form of box which is higher and narrower a pair of single arched brackets may be used to hold one bottle. In such form it is also possible to utilize a single cover panel with a handle located at its midpoint. Such panel may be moved along the guideways in either direction to uncover the opening.

While the arrangement shown includes inwardly facing grooves to receive the panel edges it is within the contemplation of the invention to provide any suitable type of guideways such as outwardly facing flanges, and to use cooperating reversely bent edges on the panels.

A modified cover panel is shown in Figure 8 in which the sheet 46 has relatively heavy and light longitudinally extending sections 48 and 50 connected in smooth curves. This gives comparative stiffness in the direction of the sections 48 and comparative flexibility at right angles thereto.

The embodiment illustrated in Figures 9 and 10 is intended to be substantially larger than the first embodiment and is suited to a variety of purposes such as a mending box, clothes hamper, etc. It includes a casing having a bottom 52, side walls 54, and end walls 56 extending somewhat above the side walls and arched in the same

general manner as the form previously described.

A partition 58 divides the casing into upper and lower compartments 60 and 62 respectively, the upper compartment being open at the top. A rectangular aperture 64 is formed in at least one side wall 54 to provide access to the lower compartment. Flanges 66 cooperate with the other parts of the casing to form guideways 68 substantially identical with those of the form of invention illustrated in Figures 1 and 2.

The upper portion of panel 70 in Figure 10 is similar to panel 28 but it is elongated sufficiently to form a closure over aperture 64 when the panel is in its upper limit position. An aperture 72 is formed in the panel 70 corresponding in size and shape to the aperture 64. When the panel is in the upper limit position the aperture 72 overlies the area 74 and hence the container is completely closed. When the panel is lowered until its outer edge 76 engages the floor the upper portion will have uncovered its half of upper compartment 60 and aperture 72 will be in registry with aperture 64 to expose the lower compartment 62. A similar panel may be provided for the opposite side of the container altho it may be imperforate if a single opening to compartment 62 is considered to be sufficient.

It will be apparent to those skilled in the art that various changes and modifications may be made in the construction and arrangement of parts without departing from the invention and it is intended that all such changes and modifications shall be embraced within the scope of the following claims.

We claim:

1. A utility container comprising: a casing having a bottom, side walls, and end walls; said end walls rising above said bottom a greater distance than said side walls and having curved upper margins; guideways formed on the inwardly facing surfaces of said end walls; and a pair of flexible panels mounted for sliding movement in said guideways; each of said panels being of substantially the same size and their combined extent in the direction of said guideways being sufficient to cover the opening at the top of the casing and to slightly overlap the upper edges of said side walls; said guideways extending down the outer faces of the side walls to the bottom of the casing and being open at their lower ends to provide ready removal of said panels.

2. A container comprising: a casing having a bottom, side walls, and end walls, and being open at the top; said end walls rising above the top edges of said side walls; guideways on said end walls having arched upper portions; cover panels slidably engaging said guideways and movable to cover and uncover the open upper end of said casing; a handle member on each of said panels adjacent their meeting edges and adapted to cooperate to form a virtual single handle when said panels are in juxtaposition to each other.

3. A container comprising: a casing having a bottom, side walls, and end walls, and being open at the top; guideways on said end walls extending substantially vertically adjacent and exterior to said side walls and being open at their lower ends for removal of said panels; cover panels slidably engaging said guideways and adapted, in lowered position, to lie closely adjacent and exterior to said side walls; and abutments carried by the inner faces of said panels adapted normally to engage the upper edges of said side walls to prevent inadvertent removal of said panels from said casing.

4. A container as claimed in claim 3; said panels being deflectable to disengage said abutments from said side walls for disassembly of said panels.

5. A container comprising: a casing having a bottom, side walls, and end walls, and being open at the top; guideways on said end walls having arched upper portions traversing the open top of said casing; cover panels slidably engaging said guideways and adapted to cover said open top when located in the upper portions of said guideways and to uncover said open top when located in the lower portions of said guideways; handle portions adjacent the upper edges of said panels to pull them to closed position; and abutments adjacent the lower edges of said panels to push them to open position.

6. A container comprising: a casing having a bottom, side walls, and end walls, and being open at the top; guideways on said end walls; supporting brackets extending from a medial portion of the inner face of each end wall to support a container of somewhat smaller lateral and longitudinal dimensions within said casing and in spaced relation to the bottom thereof; and cover means slidably engaging said guideways and movable to one position to close the open top of said casing and to another position to provide a sufficiently large opening for removal of said second container.

7. A container comprising: a casing having a bottom, side walls, and end walls, and being open at the top; guideways formed on said end walls, each guideway being formed with a pair of upright, relatively straight and parallel portions joined at their upper ends by an arched portion; a shelf within said casing intermediate the top and bottom of said side walls and dividing the casing into upper and lower compartments; at least one access opening formed in a side wall for access to the lower compartment; and a pair of cover panels slidably engaging said guideways; at least one of said cover panels being of sufficient vertical extent to reach from the bottom of the access opening to the midpoint of said arched portions; and an opening formed in an intermediate portion of said panel and adapted to register with said access opening in one position of said panel.

8. A utility container comprising: a casing having a bottom, side walls, and end walls; said end walls rising above said bottom a greater distance than said side walls; guideways formed on said end walls and having arched upper portions; and a pair of flexible panels mounted for sliding movement in said guideways; each of said panels being of substantially the same size and their combined extent in the direction of said guideways being sufficient to cover the opening at the top of the casing and to slightly overlap the upper edges of said side walls; and a handle member on each panel adjacent their meeting edges; said members combining to form a virtual single handle for carrying purposes.

9. A utility container comprising: a casing having a bottom, side walls, and end walls; said end walls rising above said bottom a greater distance than said side walls; guideways formed on said end walls and having arched upper portions; and a pair of flexible panels mounted for sliding movement in engagement with said guideways; each of said panels being of substantially the same size and their combined extent in the direction of said guideways being sufficient to cover the opening at the top of the casing and to slightly overlap the upper edges of said side walls; said guideways extending down the outer faces of the side walls to the bottom of the casing and being unobstructed at their lower ends to provide ready removal of said panels.
